UNITED STATES PATENT OFFICE.

MICAJAH R. DAVIS, OF PINK HILL, TEXAS.

SELF-FEEDING COTTON-PRESS.

SPECIFICATION forming part of Letters Patent No. 365,799, dated July 5, 1887.

Application filed December 29, 1886. Serial No. 222,913. (No model.)

To all whom it may concern:

Be it known that I, MICAJAH R. DAVIS, a citizen of the United States, residing at Pink Hill, in the county of Grayson and State of Texas, have invented certain new and useful Improvements in Self-Feeding Cotton-Presses; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention is a cotton-press; and it consists in the parts which will be hereinafter described, and pointed out in the claims.

In the accompanying drawings, Figure 1 is a top plan view of a machine embodying my 20 invention. Fig. 2 is a side elevation. Fig. 2½ is a detailed side elevation, partly in sections, of one of the two F-shaped locking-levers which engage in the frame for limiting the movement of the rotary cotton-boxes and locking 25 the same. This view also shows a side elevation of one of the two drums which alternately receive and pay out the chains which actuate the rotary boxes. The outer ends of these chains are secured to the F-shaped lever.

30 Fig. 3 is a horizontal section on the line z z of Fig. 4. Fig. 4 is a longitudinal vertical section on the line x x, Fig. 1. Fig. 5 is a cross-section on the line y y, Fig. 1. Fig. 6 is a detail plan view of the clutch mechanism, pump, 35 pulley, &c. Fig. 6½ is a side elevation of the pumping mechanism. Fig. 7 is a detail perspective view of the trigger for actuating the water-valves. Fig. 7½ is a detailed side elevation of a clutch and the arms and lever for 40 actuating the same. Fig. 8 is a perspective view of the means for reversing the clutches whereby a reverse movement is imparted to the rotary feed-boxes. Fig. 9 is a detail, partly in section, of the intermittent rotary mechanism for actuating the clutches which engage 45 the chain. The devices shown in this view (the arm J⁶) also serves to unlock the F-shaped lever so that the cotton-boxes may rotate. Fig. 9½ is a top plan view of the cam-wheel, its 50 shaft being shown in section.

Like letters indicate like parts in the several views.

The letter A indicates the base rectangular frame upon which the machine is mounted.

A¹ represents two short corner-standards on 55 one end, and A² two corner-standards on the opposite end.

A³ A⁴ are four tall standards near the center of the machine. To the rear standards, A³, is secured a semicircular wall, B. A semi-circular wall, B', is also mounted upon the front standards, A⁴.

C C are two alternate rotary boxes in and through which the cotton is alternately received and discharged into the press proper. 65 These boxes are mounted upon the front end of a shaft, C. Said shaft extends lengthwise of the machine. Its rear end is mounted in blocks C¹ C², which are secured, respectively, upon the front transverse frame-pieces. The 70 boxes consist of two rectangular compartments of equal size rigidly united.

D is a box on the rear part of the machine, in which the cotton is pressed.

Immediately under the front wall, B', is a 75 rectangular opening, B¹.

B² is an opening under the wall B.

E is the cylinder horizontally mounted on the front side of the machine and lying lengthwise thereof.

80 E' are compressor-slats, and E² a transverse block. Said slats are secured to the block E². This block is secured to the piston-shaft E¹. Each box C, the compressing-box D, and the openings B³ B⁴ are of uniform height and width. 85 The compressor-block E¹ is of a size adapted to move freely lengthwise through said openings, box C, and into the compressor-box D.

e is a small roller journaled near the bottom of the compressor-block E¹. This roller is 90 adapted to roll upon the floors of the boxes C and D, its object being to hold the block and its piston-rod in a horizontal line and prevent the former from coming in contact with the floors in its reciprocal movement. The compressor block consists of a strong transverse beam, E³, having a series of strong vertical parallel bars, E⁴, secured to its outer side. On the inner sides of the compressor-box D is a longitudinal series of spur-teeth, D'. These 95 100

teeth incline to the rear of the machine, so that the cotton may move freely into the box, but will be prevented from returning or expanding outward against the compressor-block after compression of the bale.

D² represents the floor of the box D. This floor has its rear end secured to a cross block, d. Said block is hinged to the frame by means of the pivotal rod d', Fig. 4. The top of the box D³ is also hinged in a like manner by means of a block, d², and pivotal rod d³ extending through said block and having its outer ends mounted in the side of the frame.

The heavy dark lines, Fig. 1, represent openings in the hinged top D³. Each side of the box D is provided with a door, d⁴, vertically movable in the grooved cross-block f f, Fig. 3. The other sides of said doors rest, respectively, in rabbeted corners d⁵. Strong vertical slats g are secured to the inner sides of the rear transverse frame-pieces f f, Fig. 4. These slats constitute the outer ends of the box D. Transverse blocks h h are respectively secured to the top and bottom of the frame-pieces, f f. The blocks h h are about half the width of the pieces f. The outer ends of the slats g extend above and below the pieces f, whereby transverse grooves i i are formed. The outer inner ends of the hinged top and bottom pieces, D² D³, are provided with transverse pieces i' i', which fit into the grooves i i when said hinged portions are closed. A transverse block, E³, is interposed between the outer end of the piston E² and the slats E'. The block E³ is provided on one side with two arms, e' e'. One of these arms is on the upper side of the block and the other on the lower side thereof. (See Figs. 3 and 4.) The space between the frame-pieces A⁵ A⁷ is sufficient to admit said arms. These arms extend forward and lie between the two front parallel frame-pieces A⁶ and A⁷ when the piston is in its cylinder, whereby the compressor-head and its piston are prevented from turning. Said arms also serve to hold the head in a fixed relative longitudinal position when said head receives its initial inward movement.

E⁹ represents a grooved wheel journaled immediately to and below the inner end of the cylinder. This wheel is a guide and support for the piston-rod. Said wheel is journaled in two shorta rms, SA, extending outward from the cylinder. (See Fig. 6.)

F is a wire-covered cylinder or feed-roll provided with end journals, F' F', which are journaled in the bottom of slots F² in side frame-pieces, F³, on the upper front side of the machine.

F⁴ is a top roller. F⁵ is a roller under the roller F⁴, and F⁶ is a roller whose periphery is in contact with the periphery of the wire cylinder. The outer end of each roller F⁴ F⁵ F⁶ is provided, respectively, with a cog-wheel, f⁴ f⁵ f⁶. A small cog, f⁷, is mounted under the cog f⁶. Outside of the cog f⁶, and mounted on the same shaft therewith, is a sprocket-wheel, f⁸. The greater part of the cog f⁶ is shown in

dotted lines, Fig. 2. Cog f⁶ meshes with small cog f⁷. The cog f⁷ meshes with cog f⁵, which in turn meshes with the cog f⁴, whereby when the roller F⁶, cog f⁶, and the sprocket-wheel f⁸ are rotated in the direction of the arrow the small cog f⁷ is rotated outward and the cogs f⁴ f⁵ and their rollers rotated inward, so as to draw the cotton between said rollers and force the same through the opening B³ in the front wall, B', (see Fig. 4,) and thence into one of the boxes C. The cylinder F rotates in the same direction as the upper inner roll, F⁴, and the rotary motion of the roll F⁶ is the same as the roll F⁴.

FT represent a feed-table located immediately below the cylinder F. It will thus be observed that cotton fed under the cylinder F is drawn between said cylinder and its roll F⁶, with which it is in frictional contact, and thence drawn between the rolls F⁴ F⁵. The cotton is slightly compressed by its passage between the rolls, and is forced into the upper receiving-box, C, in layers.

The letter G represents a shaft provided on its outer end with a band-wheel, G', keyed or otherwise secured thereto, the inner end of said shaft being provided with a crank-wheel, G², Fig. 6. The crank-pin G¹³ of this wheel is connected to a grooved block, G³.

G⁴ represents the pumps, and G⁵ the plunger-rods thereof. The outer ends of the plunger-rods are connected to a rectangular frame, G⁷. The grooves in the block aforesaid engage the vertical side pieces of this frame and the block slides therein when the wheel G² is rotated, whereby a reciprocating movement is given to the plungers. The wheel G² is keyed or otherwise secured to the shaft. Said shaft is mounted in bearings G⁸ G⁹.

H H' represent two flanged drums loosely mounted on the shaft G. The adjacent sides of these drums are provided with clutch-teeth h h'. A double-face clutch, h², is keyed to the shaft between the drum-clutches h h'.

h³ is a bar pivoted at h⁴ between the drums. The loose end of the bar is provided with a longitudinal slot, h⁵, which engages a crank-pin, h⁶, on the upper end of a wheel, h⁷. The under side of the bar h³ is provided with a spline, which engages a circumferential groove in the double-face clutch h², whereby a lateral movement of the bar will throw the double clutch in engagement with one or the other of the drum-clutches. There is sufficient space, however, on the shaft between the drum-clutches for the double-face clutch to rotate freely without engaging either drum-clutch, said spline and groove being shown in dotted lines, Figs. 6 and 9.

H¹⁴ represents a spiral spring secured on a short pin, H¹⁵. Said spring is provided with an arm, H¹⁵. The spring and arm serve to prevent the lateral inward movement of the drum H and clutch h on the shaft G. Keyed to the shaft on the inner side of the drum H is a collar, I, and clutch I'.

I² represents a clutch, and I³ a sprocket-

wheel. Said clutch and sprocket-wheel are rigidly united and loosely mounted on the shaft G.

I¹ is a circumferential groove in the clutch I². 5 I⁵ is a short rock-shaft secured to the frame by straps i³ i³. Said rock-shaft is provided with two upwardly-projecting arms, i⁴ i⁴. (See Figs. 6 and 7 1/2.) The outer inner sides of these arms are provided with pins i² i², which engage the groove I⁴.

I⁶ is a downwardly-projecting arm, which is a right-angled continuation of the rocker-shaft, I⁵. By means of the arm I⁶ the shaft I⁵ and its arms and pins, the clutch I², and 15 sprocket-wheel I³ may be thrown in or out of engagement with the clutch I¹. An endless sprocket chain, I⁷, Fig. 2, engages the sprocket-wheel I³ and the sprocket-wheel f⁸ on the outer end of the feed roller F⁶. It will thus be observed that when the shaft G is rotated and the clutch I² thrown into engagement with the clutch I¹ the sprocket-wheels, gear-wheels, and feed-rollers are set in motion for the purpose of drawing the cotton through the rolls 25 into the upper rotary box, C. When the box is full, the clutches I¹ and I² are disengaged, (by turning the arm I⁶), and the rolls thereby stopped until the filled box is rotated to the bottom and the lower empty box turned to the 30 top, when the feed movement is again set in motion to fill the top box.

I⁹ represents an arm secured at its upper end to one side of the roller-frame. The lower end of this arm is provided with a roller, I⁸, 35 which lies and presses against the sprocket-chain I⁷, so as to hold said chain taut.

The letter J represents a tube or sleeve provided on its upper end with a collar, J⁵, rigidly secured thereto. To the under side of 40 this collar is pivoted an end of an arm, J⁶, whose function will be hereinafter specified.

J⁷ is a short laterally-extending arm secured midway on the sleeve J. This arm is provided with an opening for the reception of the upper end of a vertically-movable pin, J².

J³ represents a collar rigidly secured to the lower end of the sleeve J. This collar is provided with an opening in vertical alignment with the opening in the arm J⁷. The lower 50 end of the pin J² fits into the opening in the collar J³. The pin J² has a vertically-reciprocating movement in the openings aforesaid, and it is provided with shoulders to limit said movement.

K is an intermittent rotary rod provided on its upper end with a small crank-wheel, h⁷, rigidly secured thereto. This wheel is provided with a pin, h⁶, which engages the slot h⁵ in the loose end of the pivoted bar h³. The 55 lower end of the rod K is mounted in a base-block, J⁷, which block is mounted on the frame-piece A⁷.

K' is a cam wheel rigidly secured on the rod K between the collar J³ and block J⁷. A plan 60 view of this cam-wheel resembles the figure S. The two hooked projections j j of said cam are adapted to alternately engage the lower

end of the pin J², whereby the sleeve J and rod K are momentarily locked, so as to rotate said rod one-fourth of a revolution. Said rod, 70 its crank-wheel h⁷, and the cam-wheel K' have an intermittent rotary movement. They are turned one fourth of a revolution at a time. The cam is alternately acted on by an arm (which will be hereinafter specified) and the locking-pin J², which causes said cam to turn with the rock movement of the sleeve. The rotary movement of the cam is in the direction of the arrow Fig. 9 1/2. The outer edges, j' j', of the cam are thin, and they taper upward to 80 the body, which is thick. By this construction the lower end of the pin J² is enabled to lock with one of the projections j, and then be moved forward and carried up the inclined wedge-shaped side of the cam, and then dropped 85 by its own weight into one of the spaces 4, so as to engage the cam and turn the same when the sleeve is rocked.

The letter L represents a plate, which is secured to the top of the frame-piece A⁷. A 90 vertical stud, L', is centrally fixed to the plate L. L² is a sleeve, which is mounted on the stud L'. This sleeve is provided with two arms, L³ L⁴.

L⁵ is an arm jointed at one end to the outer 95 end of arm L³, and also jointed at its other end to a projection on the collar J³.

L⁶ is an arm jointed at one end to the arm L⁴. The outer end of the rod L⁶ is provided with a bent-up end, L⁸. Said bent-up end is 100 adapted to alternately engage one of the two notches in the cam-wheel K'.

L⁷ is a spring for holding the arm L⁶ in engagement with said cam-wheel.

M represents an arm bolted to the rear side 105 of the compressor-block E⁸, Fig. 3.

M' is a short right-angled arm jointed at one end to the outer end of the arm M. A spring, m, engages the arms M M', so as to normally hold them at right angles, as shown. 110 This spring, however, permits the short arm M' to turn slightly outward, so as to slightly yield when it engages the arm L³ on the outward movement of the compressor-block.

N N' N² N³ represent four water-pipes in 115 communication. These united pipes constitute a rectangular frame, Fig. 6. N⁴ is also a water pipe, which communicates with the pump G⁴. The pipe N⁴ connects the two parallel pipes N N². The pipe N⁴ has an extension, N⁵. A four-way pipe, N⁶, connects the pipes N⁴ N⁵.

N⁷ is an elbow connecting the pipe N⁵ with the pipe N⁸.

N⁹ is a short pipe connecting the pipes 125 N⁷ N⁸.

N⁹ is a stop-valve in the pipe N⁸. This valve is automatically opened and closed, so as to admit water to the cylinder and pump the same therefrom, all of which will be herein- 130 after specified.

N¹⁰ is a valve in a short pipe, N¹¹.

N¹² is the induction-opening in the four-way pipe N¹³.

There are a series of stop-valves, n , in the series of pipes, which are normally open, as indicated in Fig. 6.

The letter O represents a rod provided with two outer collars, $O' O''$, fixed thereto. (See Figs. 3 and 7.) O'' is a middle collar loosely secured on said rod.

$O' O''$ are spiral springs on the rod O . Each spring is interposed between the middle and outer collars, respectively.

O'' is a toothed rack-bar, having its rear inner end secured to the loose collar O'' .

O' is a vertical rod provided on its upper end with a right-angled plate, O'' . This plate is engaged with a cross-arm piece, n^3 , which actuates the stop-valve N^9 . The arm n^3 lies against the inner side of the plate O'' . The rod O' and its plate O'' are adapted to rotate or rock one-fourth of a revolution, and thereby alternately open and close the valve N^9 by turning the valve-arm n^3 .

P represents a rod, which is secured to the fixed collars $O' O''$ at the points $p p'$. This rod P is provided with an outer rectangular end, P' , which is provided with two notches, $p^2 p^3$, in its upper side.

P^3 is a pinion on the lower end of the rod O' . This pinion engages the teeth in the rack-bar O'' .

P^4 is a collar fixed on the rod O' above the pinion P^3 . This collar has a side projection or short arm, to which is jointed the inner end of a notched bar, P^5 . This bar is provided with two notches, p^7 and p^8 , on its under side.

The bars P' and P^5 cross each other at right angles, and each is alternately adapted to slide in the other's notches. Each bar has a longitudinal movement. The bar P^5 is mounted, so that when one of its notches is in a line or immediately over the under bar, P' , the latter bar may move freely through the notch of the former. The rod P is suspended by and slides in a staple secured to the under side of the frame-piece A^5 . (This staple is not shown.)

The trigger-movement specified in this paragraph is for actuating the valve N^9 by turning its handle or arm n^3 . The initial movement is given the trigger by a chain, P^8 . One end of this chain is secured to the inner end of the

rod O . The other end thereof is secured to the rear side of the compressor-block E^3 . The arrangement is such that when the piston and its compressor-head and slats have been driven out to nearly the full length of the stroke the

chain P^8 is straightened and drawn inward, and the rod O also drawn inward. This movement of said rod draws the rod P and its notched part P' inward, the smooth part of the rod P' passing through the notch p^8 in the right-angled bar P^5 . While this action is taking place, the collar O' is being drawn inward and compressing the spring O' between said collar O' and the middle collar, O'' , the middle collar, O'' , for the time being stationary, it being held by the rack-bar O'' , which bar in turn is held by the pinion P^3 , said pinion

being held and locked by the bar P^5 , the rear notch of said bar P^5 being engaged and prevented from moving by the bar P' . When, however, the compressor-head has passed out to its extreme extent, the bar P' will have been drawn through the notch p^8 until the notch p^2 of the bar P' lies immediately under the bar P^5 .

The bar P' is then released and quickly draws back through the notch p^2 of the bar P' . The movement of the bar P' is effected primarily by the action of the compressed spring O' , which forces the rack-bar O'' inward, (in the direction of the arrow Fig. 7,) thereby turning the pinion P^3 and rotating the shaft O' one fourth

of a revolution, turning the valve N^9 so that the water may be pumped from the cylinder and the piston and compressor returned. When the compressor starts on its return, the chain sags and permits the rod O and the compressed spring to resume their normal position, as indicated in Figs. 3 and 7. On the

return-stroke of the compressor-head, when the stroke is nearly completed, the rear side of the cross-block E^3 of the compressor is brought into contact with the inner end of the rod O , whereby said rod and the rod P and its binoched end P' are forced outward.

This action compresses spring O' and forces the bar P' through the outer notch, p^7 , of the bar P^5 until the inner notch, p^3 , of the bar P' is immediately under the bar P^5 . While this outward movement of the rods $O P$ and the binoched piece P' is taking place the spring O' is being compressed and producing an outward tendency to the loose collar O'' and the rack-bar O'' .

This outward tendency of the rack-bar in turn produces a pressure on the teeth of the pinion P^3 , its shaft O' , collar P^4 , and notched bar P^5 . When, however, as before

stated, the notch p^3 in the bar P' is immediately under the bar P^5 , said bar is released and forced outward by the spring O' acting through the medium of the rack O'' , its pinion, shaft, and collar.

P^{13} represents the housing provided with openings for the reception of the notched bars $P' P^5$, and P^{14} are straps for engaging the housing and connected parts to the side of the cylinder.

The front part of the cotton-boxes $C C$ is provided with a circular flange, Q , secured thereto. (See Fig. 5.) On the periphery of this flange are two F -shaped levers, $Q' Q''$, each on opposite sides. The body portions of

these levers are curved, so as to conform to the curve of the flange to which they are secured. The small ends of the levers are pivoted to the flange, so that the two-forked points thereof shall extend outward. To the loose

end of each lever is secured a separate chain, $Q^3 Q^4$, each equal in length to one-half the diameter of the flange Q . The outer ends of these chains pass through an opening, Q^5 , in one side of the front wall, B , and each of said outer ends is respectively secured to the loose flanged drums $H H'$ on the shaft G . Two

flanged pulleys, Q^6 Q^7 , are journaled in the sides of this opening. Each pulley serves as a guide for one of the chains Q^3 Q^4 .

The box-flange Q is provided with a series 5 of projections, q , which are placed in convenient places to hold the chains Q^3 Q^4 on the rod J^6 (see Figs. 2, 2½, 5, and 8) extends 10 riphey of said flange. The inner end of the through the wall-opening Q^5 , and it is provided with a bent piece, Q^9 , whose body lies at right angles to the rod J^6 . This bent piece alternately serves to disengage the levers from their locked position with the pulleys Q^6 Q^7 . The two right-angled projections q' q^2 of the 15 F-shaped lever Q^2 are adapted to close in on their respective pulleys and lock the boxes and at the same movement force the piece Q^9 and its arm J^6 outward.

The operation is as follows: When the boxes 20 are thus locked by one of the levers Q' Q^2 , the lever I^6 , Figs. 6 and 7½, is turned so as to engage the clutches I^1 I^2 , and the feed-rollers are thus set in motion, whereby the box on top 25 may be filled with cotton. It should be understood that the band-wheel G' rotates continuously in the direction of the arrow Fig. 6. While the top box is being filled the lower box (which is presumed to have been previously filled) is in a line with the compressor-head. The action of the pumps during the 30 filling of the upper box forces water into the outer end of the cylinder, thereby forcing out the piston and driving the compressor-head through the lower box and compressing the 35 cotton in the box D , Fig. 4. As each bale is pressed, it is tied off or bound, and then dropped through the lower hinged door, D^2 . When the compressor-head has reached the outer end of its stroke, the trigger, hereinbefore specified, 40 is actuated to reverse the position of the valve N^9 , Fig. 7. By the changed position of said valve, and by manipulating the water-valve N^{10} , the action of the pumps on the cylinder is reversed and the water withdrawn, so as to 45 return the compressor-head and draw it back out of the lower box. During the time the compressor-head is passing outward and backward the top box is presumed to be filled and ready to be turned to the bottom, so that its 50 contents may be pressed. On the return-stroke of the piston and compressor-head the arm M' (see Fig. 3) encounters the arm L^4 , whereby said arm is turned and with it the arms L^5 L^6 . This movement of arm L^6 slightly turns the 55 sleeve J and its top and bottom collars, J^5 J^3 . The collar J^5 by this movement forces in the rod J^6 and the bent piece Q^9 , Figs. 5 and 8, on the end of said rod, which action disengages one of the levers Q' Q^2 from its locked 60 position with its pulley, thereby leaving the boxes free to make the next half-revolution. While the boxes are locked, (they are alternately locked by the F-shaped levers Q' Q^2), the top box is being filled and the contents of 65 the lower one being compressed. It is therefore essential during this operation that the

double-faced clutch h^2 , Fig. 6, should be out of engagement with both drum-clutches, at the same time permitting the pump mechanism to work freely to force the piston out and in—that is to say, the boxes, drums, and connecting-chains lie idle while the upper box is being filled and the contents of the lower box compressed. When one of the levers Q' Q^2 is disengaged and unlocked from its pulley, the 70 shaft K and wheel h^1 , Figs. 3 and 9, are rotated one-fourth of a revolution by the action of the arms M M' L^5 L^6 , and the lever h^3 , Fig. 6, which actuates the double-faced clutch, is turned so as to throw said clutch in engagement with one of the drum-clutches, so that the rotary movement of said clutches will effect the drawing out and winding of one of the box-chains on its drum, while the chain on the companion drum will be paid out and unrolled from its drum. When the lever Q' or Q^2 , attached to the chain which is being wound, reaches its pulley, (the boxes then being in a line, one above the other,) the ends q' q^2 (see Fig. 2½) of said lever are drawn into the frame-opening Q^5 , thereby forcing out the piece Q^9 and rod J^6 and again locking the boxes. Only one lever is locked at a time, and the boxes first rotate to the right and then to the left. Strong rods R R brace the frame of the machine. The outer ends of these rods are 95 threaded and provided with bolts.

Having thus described my invention, I claim as new and desire to secure by Letters Patent—

1. The combination, with two rotary cotton-boxes having open ends, of a compressor-box having an open end in communication with one of the rotary boxes, a cylinder and piston-rod, said rod being in a line with the compressor-box and provided with a compressor-head, substantially as described. 100

2. The combination of the feed-rolls F^4 F^5 F^6 , each provided with an end cog-wheel, the cogs of the rolls F^4 F^5 being engaged, an independent cog-wheel in engagement with the cogs of the rolls F^5 F^6 , a sprocket-wheel secured to the outer end of the roll F^6 , the main shaft G , the sprocket I^3 , an endless sprocket-chain in engagement with the sprocket-wheels aforesaid, and a clutch for engaging the sprocket-wheel I^3 , with its shaft, substantially as described. 110

3. The combination of the shaft G , provided with the sprocket-wheel I^3 and grooved clutch I^2 , rigidly united and loosely mounted on said shaft, the clutch I' , fixed to said shaft, and of the shaft I^5 , having handle I^6 , said shaft I^5 , being provided with arms and pins for engaging the grooved clutch aforesaid, whereby the clutch I^2 and its sprocket-wheel may be thrown in and out of gear, substantially as described. 120

4. The combination of the rotary shaft K , provided on its lower end with the S-shaped tapering cam K' , the sleeve J , provided with two collars having openings in vertical alignment, a shouldered pin mounted in said openings, the rod L^5 , having its outer end in piv- 130

otal engagement with one of the collars on the sleeve aforesaid, the spring-actuated rod L^6 , adapted to alternately engage the notches in the cam, and means for actuating said arms, 5 substantially as described.

5. The combination of the rotary shaft K , provided on its lower end with the S-shaped tapering cam K' , the sleeve J , provided with two collars having openings in vertical alignment, a shouldered pin mounted in said openings, the rods $L^5 L^6$, having their outer ends in engagement, respectively, with one of the sleeve-collars and the cam aforesaid, the pivoted arms $L^3 L^4$, rigidly united and being at 10 right angles, the outer ends of said arms being jointed to the inner ends of the rods aforesaid, substantially as described.

6. The combination of the compressor-head provided on its front side with the arm M , the 20 outer end of said arm being provided with a spring-actuated arm jointed thereto and normally at right angles therewith, the united pivoted arms $L^3 L^4$ at right angles to each other, the rods $L^5 L^6$, the sleeve J , provided 25 with the collars and openings, the shouldered pin mounted in said openings, and the rod K , provided on its lower end with the S-shaped tapering cam, the several parts being arranged and combined substantially as specified.

30. 7. The combination of the rod O , provided with the rigid collars $O' O^2$, and the loose collar O^3 , also provided with the spiral springs $O^4 O^5$, the toothed rack-bar O^6 , having its inner end engaged to the loose middle collar, O^3 , the rod O' , provided on its lower end with the pinion P^8 , said pinion being in engagement 35 with the rack O^6 , the top binotched bar, P^5 , jointed to an arm on the rod O' , and the lower binotched bar, P' , secured to the collars $O' O^2$, substantially as described.

40. 8. The combination, with the compressor-block E , rod O , and connecting-chain P^8 , of the

collars $O' O^2$, rigidly secured to said rod, the loose middle collar, O^3 , and spiral springs $O^4 O^5$ on said rod, the toothed rack-bar O^6 , having its inner end connected with the loose collar O^3 , the rod O' , provided on its lower end with the pinion P^8 , said pinion being in engagement 45 with the rack O^6 , the top binotched bar, P^5 , jointed to an arm on the rod O' , and the lower binotched bar, P' , secured to the collars $O' O^2$, substantially as described.

9. The combination of the rod O , provided with the rigid collars $O' O^2$, and the loose middle collar, O^3 , also provided with the spiral springs $O^4 O^5$, the toothed rack-bar O^6 , having its inner end engaged to the loose middle collar, O^3 , the rod O' , provided on its lower end with the pinion P^8 , said pinion being in engagement 55 with the rack O^6 , the binotched bar P^5 , jointed to an arm on the rod O' , the rod P , secured to the rigid collars $O' O^2$, and the binotched bar P' , formed on the outer end of the rod P , substantially as described.

10. The combination of the rod O , provided with rigid collars $O' O^2$, and the loose collar O^3 , also provided with the spiral springs $O^4 O^5$, the toothed rack-bar O^6 , having its inner end connected to the loose middle collar, O^3 , the rod O' , provided on its lower end with the pinion P^8 , said pinion being in engagement 65 with the rack O^6 , the top binotched bar, P^5 , jointed to an arm on the rod O' , the lower binotched bar, P' , secured to the collars $O' O^2$, the plate O^8 , secured to the upper end of the rod O' , and the valve N , provided with the arm n^3 , said arm being in engagement with the plates O^8 , substantially as described.

In testimony whereof I affix my signature in presence of two witnesses.

MICAJAH R. DAVIS.
